UNITED STATES PATENT OFFICE.

ERNEST S. PECK, OF CLEVELAND, OHIO.

PERCOLATOR.

No. 925,835.

Specification of Letters Patent. Patented June 22, 1909.

Application filed January 26, 1909. Serial No. 474,242.

To all whom it may concern:

Be it known that I, ERNEST S. PECK, a citizen of the United States, and a resident of Cleveland, county of Cuyahoga, and State of Ohio, have invented a new and useful Improvement in Percolators, of which the following is a specification, the principle of the invention being herein explained, and the best mode in which I have contemplated applying that principle, so as to distinguish it from other inventions.

The general class of apparatus to which the present invention relates, is that designed for the extraction of soluble oils and fats as from tankage or other analogous material forming one of the products of garbage reduction plants and rendering establishments, or from the various oil bearing seeds. As is well understood, the solvent generally employed for the purpose of taking up the grease in the case of tankage, is naphtha; but whether naphtha or other solvent be used a sufficient quantity is passed through the material to thoroughly extract such grease, after which extraction it becomes necessary to recover the portion of the solvent that has been absorbed by the material, the quantity of the solvent being proportionately quite considerable, and the loss, unless it is thoroughly recovered, being a large item of expense in the carrying on of the operation referred to.

The object of the present invention is the provision of a more efficient and labor saving apparatus for the purpose of effecting both such extraction and recovery steps of the general process just described, and one that will be economical both by reason of the thoroughness with which the naphtha is recovered, and the small amount of power and labor required to operate the apparatus.

To the accomplishment of these and related ends, said invention, then, consists of the means hereinafter fully described, and particularly pointed out in the claims.

The annexed drawings and the following description set forth in detail certain mechanism embodying the invention, such disclosed means constituting, however, but several of the various mechanical forms in which the principle of the invention may be used.

In said annexed drawings:—Figure 1 represents a central longitudinal cross-section of a percolator embodying my several improvements, together with a condenser attached thereto for the purpose of recovering the naphtha vapors driven off from the tankage

in the percolator after completion of process of extraction; Fig. 2 is a similar sectional view of the percolator proper, but in a different operative position, and including certain modifications in construction; and Fig. 3 is a partial end elevation and partial transverse section of such modified form of percolator.

Referring to the figures just described, the percolator will be seen to comprise essentially a cylindrical drum A disposed in a substantially horizontal position and rotatably supported upon roller bearings a. To this end it is provided with annular bearing rings a' adapted to rest on such rollers, and with a gear a² at one end wherewith suitable driving means may be connected, as will be readily understood. Such drum is provided in its lateral surface with a longitudinal extending series of man-holes a³, three in number as shown, through which the material to be treated may be introduced into the interior of the drum, and thence in turn discharged. Such man-holes are adapted to be closed by means of covers a⁴, except when the material is being thus passed therethrough. Disposed longitudinally of the drums, and laterally adjacent to said man-holes, is a pipe B that is connected with draining means associated with said man-holes, two diverse forms of such means being illustrated in Figs. 1 and 2 respectively. As shown in said first figure a screen b is provided transversely of each man-hole so as to separate off a portion of the same. Any liquid collecting therein, after seeping through the mass of material within the drum, is conducted to the longitudinally extending pipe by means of the connecting pipes b', which latter are controlled by suitable valves b². In the construction shown in Fig. 2, I provide a perforated plate B' that extends the entire length of the drum and preferably close along one side of the man-holes, although this is not necessary, for such plate may be located at a greater or less distance therefrom just as well, providing a corresponding change be made in another part presently to be described. Plate B' is spaced from the inner wall of the drum, so as to afford a place for the liquid to collect, connections b' with such space, serving as before to conduct such liquid to the longitudinally extending pipe B.

Substantially diametrically opposite the longitudinal pipe B (whether the latter lies adjacent to man-holes a³ or not) is a second

longitudinally disposed pipe C through which either naphtha or steam is designed to be supplied to the interior of the drum as required. Connection between such pipe and the drum's interior is had by means of transversely disposed pairs of branch pipes c respectively controlled by valves c', the inner ends of each pipe being connected with T's ranged longitudinally along the pipe. For supplying the steam to longitudinal pipe C, a connection c², alined with the axis of the drum, is provided, such connection being permanently made through a suitable stuffing box c³, whence radially extends a valve-controlled branch c⁴ to the projecting end of said pipe C. The latter is further provided with an extension c⁵ to which a connection C' as a hose or the like may be joined when it is desired to supply naphtha in place of steam to the drum. The other longitudinal pipe B is adapted to be similarly connected with a flexible connection B² permitting the removal of the excess of naphtha drained from the tank.

The operation of the apparatus thus far described, may be readily indicated. The position of the drum shown in Fig. 1 is that which it will normally occupy while being filled with tankage, as also while the naphtha absorbed by the material is being driven off in the last stage of the operation. When the drum is thus disposed, the covers closing the man-holes may be removed and the drum filled, preferably from $\frac{1}{2}$ to $\frac{2}{3}$ full of tankage. Such man-holes being then closed, the drum is rotated and left in a position substantially a half-turn over; thereupon its interior is flooded with naphtha either through pipe C and its branch connections c, or, as is sometimes initially desirable, through pipe B (now disposed lower-most) so that such solvent may rise upwardly through the material. The excess of naphtha, with the grease in solution, after percolating through the mass of tankage is withdrawn through the draining means shown as associated with the man-holes. In order to insure thorough contact between the solvent naphtha and all of the material it may become desirable in connection with certain materials, during this process, to rotate the drum one or more times, thus thoroughly intermingling such contents and naphtha, whereupon the process of draining off the latter may be again continued. During rotation of the drum, exterior connections with the two longitudinal pipes are, of course, temporarily broken.

When the extraction of grease and other valuable constituents has been thus completed, the recovery of the naphtha still remaining in the tankage, is effected by supplying steam through the same connections c, by which the naphtha had previously been admitted to the tank's interior. The posi-

tion of the tank, however, is again changed, so as to now dispose longitudinal pipe C and such connections on the under side, in order that the steam may have to pass through the mass of tankage before it can escape from the drum. Such escape of the steam, together with the associated naphtha vapors, is by the way of a pipe D, supported exteriorly of the drum and passing through a suitable stuffing box d in the end thereof opposite to that at which the steam is supplied. A plate d' serves as a shield for the inner end of the pipe, to prevent the entrance therein of the solid material being treated. Exteriorly of the drum, such vapor discharge pipe D is connected with a condenser D' (Fig. 1) that comprises a main condenser coil d² in a tank d³ containing a suitable cooling liquid. Such condenser coil d² is provided with a liquid discharge d⁴ and with a vapor discharge d⁵ the latter opening below the liquid level in the tank whereby a liquid seal is formed therefor. A secondary condensing coil d⁷ is interposed between the discharge end of the main coil and such vapor discharge, and a loop d⁸ is likewise provided, being made of a sufficient height to prevent the water of the tank from rising and flowing over into coil d⁷. It will thus be seen that all air or other inert gases in the apparatus will be eliminated by way of discharge d⁵ upon admitting steam to the tank; but that immediately upon steam or naphtha vapor coming in contact with the cool condenser coil, their liquefaction produces a vacuum sufficient to raise the water to a greater or less height in the outer arm of the loop d⁸ with the resulting seal, already noted.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A percolator comprising a rotatable, substantially horizontal drum provided with a series of longitudinally alined man-holes in its cylindrical wall for the supply and discharge of the material to be treated; connections to the portion of such wall substantially diametrically opposite from said man-holes for introducing either solvent or steam as desired; and draining means connected with such wall contiguously to said man-holes.

2. A percolator comprising a rotatable, substantially horizontal drum provided with a series of longitudinally alined man-holes in its cylindrical wall for the supply and discharge of the material to be treated; two pipes disposed longitudinally of said drum, the one adjacent to said man-holes, the other substantially diametrically opposite there-

from; means for draining the interior of the drum connected with the first of said pipes; and means for supplying either a solvent or steam to the other thereof, said last-named 5 pipe having discharge connections to the drum's interior, said draining and solvent supplying means being separable from the corresponding pipes, respectively.

3. A percolator comprising a rotatable, 10 substantially horizontal drum provided with a series of longitudinally alined man-holes in its cylindrical wall for the supply and discharge of the material to be treated; two pipes disposed longitudinally of said drum, 15 the one adjacent to said man-holes, the other substantially diametrically opposite therefrom; means for draining the interior of the drum connected with the first of said pipes; and means for supplying either a solvent or 20 steam to the other thereof, said last-named pipe being provided with transversely ranged discharge branches connected to the drum at their outer ends, said draining and solvent supplying means being separable from the 25 corresponding pipes, respectively.

4. A percolator comprising a rotatable, substantially horizontal drum provided with a series of longitudinally alined man-holes in its cylindrical wall for the supply and 30 discharge of the material to be treated; two pipes disposed longitudinally of said drum, the one adjacent to said man-holes, the other substantially diametrically opposite therefrom; a perforated draining plate within said 35 drum and alongside said man-holes, the space between said plate and the drum wall being connected with the first of said pipes; means for supplying either a solvent or steam to the other of said pipes, said last-named 40 pipe being provided with longitudinally ranged T's; and transversely disposed discharge branches connected at their inner ends with said T's and at their outer ends with the drum wall.

45 5. A percolator comprising a rotatable, substantially horizontal drum provided with a series of longitudinally alined man-holes in its cylindrical wall for the supply and discharge of the material to be treated; connections to the portion of such wall substantially diametrically opposite from said man-holes for introducing either solvent or steam as desired; means for draining liquid from 50 said drum connected with such wall contiguously to said man-holes; and a pipe centrally connected with one end of said drum for withdrawing vapors therefrom.

6. A percolator comprising a rotatable,

substantially horizontal drum provided with a series of longitudinally alined man-holes 60 in its cylindrical wall for the supply and discharge of the material to be treated; circumferentially spaced connections to the portion of such wall substantially diametrically opposite from said man-holes for introducing 65 either solvent or steam as desired; means for draining liquid from said drum connected with such wall contiguously to said man-holes; and a pipe centrally connected with one end of said drum and bent upwardly inside the same for withdrawing vapors therefrom.

7. A percolator comprising a rotatable, substantially horizontal drum provided with a series of longitudinally alined man-holes 75 in its cylindrical wall for the supply and discharge of the material to be treated; two pipes disposed longitudinally of said drum, the one adjacent to said man-holes, the other substantially diametrically opposite therefrom; means for draining the interior of the drum connected with the first of said pipes; means for supplying either a solvent or steam to the other thereof, said last-named pipe 80 having discharge connections to the drum's interior; and a pipe centrally connected with one end of said drum and bent upwardly inside the same for withdrawing vapors therefrom.

8. A percolator comprising a rotatable, 90 substantially horizontal drum provided with a series of longitudinally alined man-holes in its cylindrical wall for the supply and discharge of the material to be treated; two pipes disposed longitudinally of said drum, 95 the one adjacent to said man-holes, the other substantially diametrically opposite therefrom; means for draining the interior of the drum connected with the first of said pipes; means for supplying either a solvent or steam 100 to the other thereof, said last-named pipe being provided with transversely ranged connections connected to the drum at their outer ends, said draining and solvent supplying means being separable from the corresponding pipes, respectively; and a pipe centrally connected with one end of said drum and bent upwardly inside the same for withdrawing 105 vapors therefrom.

Signed by me this 11th day of January, 110
1909.
